UNITED STATES PATENT OFFICE.

RAYMOND JOHN SHRIMPTON, OF EXETER, ENGLAND, ASSIGNOR OF ONE-HALF TO
THOMAS O'BRIEN LIMITED, OF LIVERPOOL, ENGLAND, A COMPANY OF GREAT
BRITAIN.

TILL:

1,411,067.

Specification of Letters Patent. Patented Mar. 28, 1922.

Application filed April 9, 1921. Serial No. 459,828.

To all whom it may concern:

Be it known that I, RAYMOND JOHN SHRIMPTON, a British subject, residing at Exeter, county of Devon, England, have invented certain new and useful Improvements in Tills, of which the following is a specification.

This invention relates to a mechanical or automatic holder for paper money such as treasury or dollar bills or notes.

The paper holder includes a spring supported table upon which the bill or note is placed, rotary operating fingers to hold the bill or note pressed down upon the table and means connecting the table with the fingers so that by the depression of the table, the fingers are caused to rotate and hold the bill or note upon the table.

It will be fully described with reference to the accompanying drawings.

Fig. 1 is a front elevation partly in section.

Fig. 2 is a plan.

Fig. 3 is a transverse section.

Fig. 4 is a perspective view.

The table A upon which the bills or notes are laid is supported by a spring *a* and pivoted by brackets *a'* at each end to a pair of levers *B B'* by which as it is depressed it is maintained horizontal. A transverse bar *C* extends across below the table A from end to end. Below the bar a rocking lever *C'* is pivoted, which is forced downwards by the bar *C* when the table A is depressed.

Above the table A a pair of cranked or eccentric fingers *D* are mounted to rest upon the top of the notes *A'* on top of the table A, the upward pressure of the spring *a* causing the table A to press the notes against the fingers *D* when in normal position. The fingers *D* are journalled in suitable bearings *d* in which their shanks can rotate. The shank of each is formed with a short crank *d'* and fitted with a grooved pulley *E*. The

crank *d'* is connected to a spring *d''* by which it is drawn down to the bottom dead centre. The grooved pulley *E* is loose upon the shank of the finger *D*, the face *e* forming one member of a clutch of which the other member *E'* is fast on the shank. Upon the grooved pulley *E* two cords *e' e''* are attached one wound upon it in one direction, and the other wound upon it in the reverse direction. The cord *e'* is attached to the free

end of the rocking lever *C'* and the cord *e''* to a spring *F*.

In operation a bill or note is laid upon the table A, the hand of the operator resting between the two fingers *D* and depressing the table against the pressure of the spring *a*. The table A under pressure swings downward on the levers *B B'* which maintain it horizontal, and the cross bar *C* contacts with the rocking lever *C'* moving it downward. The downward movement of the rocking lever pulls on the cords *e' e''* and rotates the two crank fingers *D* in opposite directions, and lifts them off the bills or notes on top of the table A. The rotation of the grooved pulleys *E* which are loose on the shanks of the fingers *D* but engage with the clutch member *E'*, rotate about half a revolution and carry the cranks *d'* over the top dead centre, whereupon the pull of the spring *d''* on these cranks completes the revolution of the fingers *D* the clutch members *E'* rotating past the clutch faces of the pulleys *E*. This movement of the crank fingers *D* spreads out the bill or note and then firmly holds it. The table A is then released and is forced upward again by the spring *a* into normal position. This movement also permits the rocking lever *C'* to rise, it being pulled up by the action of the springs *F*, pulling on the cords *e''* and winding them off the pulleys *E* at the same time rewinding the cords *e'* on the pulleys in the reverse direction.

What I claim as my invention and desire to protect by Letters Patent is:—

1. In a holder for paper money, the combination with a spring controlled table and spring to hold it in normal position and raise it when depressed of radius levers upon which the table swings to maintain it horizontal, a rocking lever which is depressed by the table, a pair of cranked fingers above the table to engage the bills or notes, and means connected to the rocking lever to rotate the cranked fingers as the table is depressed substantially as described.

2. In a holder for paper money the combination with a spring controlled table and spring to hold it in normal position and raise it when depressed of a rocking lever which is depressed by the table, a pair of cranked fingers above the table to engage the bills or notes when placed thereon, a

5 pulley, clutch and crank on the shank of each of the cranked fingers, cords to attach the rocking lever to the pulleys to rotate them and the cranked fingers part of a revolution, springs to rotate the pulleys in the reverse direction, cords to connect the pulleys to the springs and springs connected to the cranks to rotate the cranked fingers the remainder of a revolution substantially 10 as described.

15 3. A holder for paper money comprising in its construction a spring controlled table upon which the bill or note is laid, a spring to maintain the table in normal position and raise it after being depressed, radius levers upon which the table swings to maintain it horizontal, a rocking lever placed below the table which is operated by the table when it is depressed, a pair of rotary cranked fingers mounted horizontally above 20

the table provided with cranks on their shanks, pulleys mounted loosely on, and clutch members affixed to the shanks of the cranked fingers, cords attached to the pulleys and rocking lever to rotate the cranked fingers part of a revolution as the table is depressed, springs attached to the cranks to rotate the cranked fingers the remainder of a revolution, and cords and springs connected to the pulleys to rotate them back 25 again to normal position substantially as described. 30

In testimony whereof I have hereunto set my hand in presence of two subscribing witnesses.

RAYMOND JOHN SHRIMPTON.
